UNITED STATES PATENT OFFICE.

WILLIAM WITTLINGER, OF CLEVELAND, OHIO.

PROPELLING MECHANISM FOR CASH OR BUNDLE CARRIERS.

SPECIFICATION forming part of Letters Patent No. 600,628, dated March 15, 1898.

Application filed October 9, 1897. Serial No. 654,714. (No model.)

To all whom it may concern:

Be it known that I, WILLIAM WITTLINGER, a citizen of the United States, residing at Cleveland, in the county of Cuyahoga and State of Ohio, have invented certain new and useful Improvements in Propelling Mechanism for Cash or Bundle Carriers; and I do hereby declare the following to be a full, clear, and exact description of the invention, such as will enable others skilled in the art to which it appertains to make and use the same.

The object of my invention is to provide a cheap, neat, and durable mechanism for delivering a propelling impulse to a cash or bundle carrier. It has been common heretofore to furnish such impulse by means of stretched elastic cord, but these cords deteriorate and lose their elasticity and require frequent renewals. My invention overcomes this difficulty by using a helical spring so arranged and supported as to be very efficient in service and neat in appearance.

The invention may best be said to consist in the combination of parts hereinafter described, and definitely pointed out in the claims.

The drawings show my invention embodied in the best form at present known to me.

Figure 1 is a side elevation of such embodiment; Fig. 2, a plan thereof; Fig. 3, a horizontal section on line 3 3 of Fig. 1; and Fig. 4, a vertical section on the line 4 4 of that figure, looking in the direction of the arrow.

Referring to the parts by letter, A represents a substantially vertical standard depending from the ceiling or otherwise supported and carrying at its lower end a peculiarly-shaped casting or head a. The standard is braced by the guy-rod a', extending from the head a, or by other or additional guys. The head a is preferably hollow throughout and has an elbow a² at its lower end. From this elbow there projects in the direction in which the car is to travel a rod B, preferably square in cross-section. The wire C, forming the path for the car, extends through a longitudinal hole in the rod B and terminates in the eye D, which is within the elbow of the head a, and the shank of which extends through that head and carries a nut d, by which the tension on the wire may be adjusted.

Surrounding the rod B is a helical spring E, secured at its rear end to the block F and at its forward end to the block G, the former block being slideable upon the rod B and being preferably rectangular in cross-section and the latter block slideable upon the wire C and being preferably round.

H represents the car for cash or bundles, which is suitably supported by wheels on the wire C and is adapted to be acted upon in its terminal position by the helical spring. The forward block G bears against the car in this position through the intervention of the rubber buffer-block O. A similar buffer-block O' on the rear side of the block G relieves shock when that block bears against the forward end of the rod B, while a third buffer, in the form of a rubber washer P, surrounding the rod B, forms a cushion between the block F and the elbow a². The rod B, being square in section, prevents turning of the block F as it slides and forms a sufficient support and guide for the helical spring without occasioning undue friction.

The head a extends forward above the rod B preferably in the form of a tube a³, having a web a⁴ on its upper side. To the forward end of this web is pivoted a latch J, the pivoting being accomplished through the intervention of the plate K, which is hinged by a pivot-bolt j to the rear end of said latch and is bolted to said web (preferably adjustably) by a bolt k. This latch J consists of the plate j', having the U-shaped bail j² extending forward and downward therefrom, as shown. The forward end of this bail is adapted to take over a hook or projection h on the car H and thereby retain the latter. A set-screw j³, extending through the plate j' and bearing against the forward end of the web a⁴, limits the downward movement of the latch J.

Pivoted to the web a⁴, preferably a little back of and below the pivot of the latch J, is the operating-lever L. This lever, which is preferably an integral casting, is composed of two side bars l, standing on each side of the tube a³ and the spring E and uniting at l' and there merging into a shank for the handle l², and also uniting in front of the pivot of the lever and forming the two arms l³ and l⁴. The lever is preferably curved, as shown, and through the two side bars thereof are

formed the curved slots b^5 . A pin f projects laterally in each direction from the block F into these slots, whereby when the lever is moved forward the block F moves with it and the spring E is compressed behind the car.

5 A helical spring M stands within the tube a^3 and has its forward end secured to the arm l^4 of the lever L and its rear end to the casting a by means of the shanked eye m or in other suitable manner. This spring thus exerts its tendency to draw the lever L into its rear position.

Extending upward from the arm l^3 of the lever is the bar N , which has its upper end 15 bent to form a lip n , which projects over the plate j' of the latch J . When the lever L is approaching its extreme forward position, the forward end of the arm l^3 impinges against the under side of the plate j' , as shown in 20 dotted lines in Fig. 1, and lifts that latch, releasing the car, and the lip n limits the upward movement of the latch under the impulse thus given it.

The parts at rest being as shown in Fig. 1, 25 the operation of the propelling mechanism is as follows: The lever L is forced forward by the hand of the operator, who grasps the handle l^2 . This movement of the lever drives the block F forward and compresses the spring 30 E between that block and the car, the rod B preventing any distortion of the spring. When the lever L has been drawn into the position shown in the dotted lines in Fig. 1, the spring is sufficiently compressed to force the 35 car the required distance and the forward end l^3 of the lever impinges against the under side of the latch J , and thus the continued movement of the lever withdraws the latch and frees the car, which the spring E , elongating, 40 propels.

The car, arriving at its destination, is stopped by the spring E of the correlative mechanism, together with the various rubber cushions referred to, while the operating-lever L is returned to its initial position by the 45 spring M , the mechanism being thus brought into position to receive the car as it returns.

Having thus described my invention, I claim—

50 1. In a mechanism for propelling a cash or bundle carrier, in combination, a standard, a stationary rod extending therefrom, a helical spring surrounding said rod, a track for the carrier extending from the forward end of said rod, means for compressing the spring while around said rod so as to bear against a carrier on the track, and means for releasing such carrier when the spring is compressed the desired amount, substantially as described.

2. In a cash or bundle carrier and mechanism for propelling it, in combination, a standard, a rod extending from the same, a wire adapted to support a car extending from the 65 forward end of said rod, a block surrounding said wire and slidable thereon, another block surrounding said rod and slidable thereon, a

helical spring surrounding said rod and secured at its ends to said blocks, means for holding stationary the forward one of said blocks, and means for forcing forward the rear one of said blocks, whereby said spring is compressed, and means for releasing said spring when compressed, substantially as described.

3. In a mechanism for propelling a cash or bundle carrier, a standard, a wire leading therefrom, a latch pivoted to an arm projecting from said standard and adapted to hook over and retain a carrier at one of its terminal positions on said wire, a lever adapted to 80 compress a spring against said carrier and having an arm which impinges against said latch and withdraws it from the carrier when the spring is compressed in combination with such spring, substantially as described.

4. In a propelling mechanism for a cash or bundle carrier, in combination, a standard, a rod projecting therefrom, and an arm projecting from the standard above said rod, a block surrounding said rod and having a pin 90 projecting laterally from it, a lever pivoted to said arm and having a slot in which said pin takes, a spring surrounding the rod and connected at its rear end to said block and adapted at its forward end to bear against a 95 carrier on a track, means for so retaining such carrier whereby when said lever is forced forward said spring is compressed against the carrier and means for releasing the carrier when the spring is properly compressed, substantially as described.

5. In a cash or bundle carrier and mechanism for propelling it, in combination, a standard A carrying a head or casting a , a rod B extending forward from said casting, an arm 105 extending forward from said casting above said rod, a lever L pivoted to said arm and passing on both sides of said rod, a block F on said rod between the two side bars of the lever, pins on said block projecting into slots 110 in said side bars of the lever, whereby when the lever is swung forward on its pivot the block F is compelled to move forward on the rod B , a wire extending from the forward end of the rod B , a block G slidable upon said 115 wire, a helical spring surrounding the rod B and secured at its forward end to the block G and at its rear end to the block F , and means for holding stationary the block G , whereby when the lever L is swung forward 120 said spring E is compressed, and means for releasing said block G and letting it act upon a carrier when the spring is compressed the desired amount, substantially as described.

6. In a propelling mechanism for a cash or bundle carrier, in combination, the standard A , the head or casting a , the tubular arm a^3 projecting forward from the same, a web a^4 formed on the upper side of said arm, a lever L pivoted to said web and having an arm l^4 , a spring M within said tubular arm secured at its rear end to a stationary part and at its forward end to said arm l^4 , a latch J pivoted to the forward end of said web a^4 , an arm l^3

of said lever adapted to impinge against said latch and elevate it, a carrier supported on a track and adapted to be engaged and retained by said latch J and a spring adapted to be compressed against said carrier by said lever L, whereby the forward movement of said lever compresses such spring and then raises the latch J to release the carrier, and the rear movement of said lever is insured by said 10 spring M, substantially as described.

7. In a propelling mechanism for a cash or bundle carrier, in combination, a wire C attached at its end, a rigidly-supported rod B surrounding said wire, a block F surrounding said rod, the block G surrounding said wire near the end of said rod B, a spring E surrounding said rod B and secured at one end to said block F and at the other end to said block G, a latch adapted to retain a carrier 20 on the wire C in front of the block G, elastic buffers between the carrier and block G, between the block G and rod B, and back of the block F, and means for compressing said spring and operating said latch to release the 25 carrier, substantially as described.

8. In a propelling mechanism for a cash or bundle carrier, in combination, the standard A, the head or casting a having an elbow a² at its end, a rod B rigidly projecting from said 30 elbow, a wire C extending from said rod and terminating at or near said elbow, a block F slidable on said rod, a block G slidable on said wire, a spring E surrounding said rod and secured at its forward end to said block G and

at its rear end to said block F, an arm projecting from said head or casting a above said rod B, a latch pivoted to said arm and adapted to retain a carrier on the wire C in front of said block G, a lever L pivoted to said arm and adapted by its movement to compress 40 said spring, and means for operating said latch to release said carrier when the spring is compressed to the desired amount, substantially as described.

9. In a mechanism for propelling a cash or bundle carrier, in combination, a standard A, a head or casting a, an arm extending forward from the same, a plate K adjustably bolted to the forward end of said arm, a latch J hinged to said plate, a set-screw $\frac{7}{8}$ limiting 45 the downward movement of said latch, said latch being adapted to engage a cash or bundle carrier supported on a track, a lever pivoted intermediate of its ends and having one end adapted to impinge against said latch J, 50 whereby said lever may elevate said latch and thereby release such carrier, a bar carried by said lever limiting the upward movement of said latch and means for supplying a force to said latch while it is still retained by said 55 latch and until said latch releases said carrier, substantially as described.

In testimony whereof I affix my signature in presence of two witnesses.

WILLIAM WITTLINGER.
